UNITED STATES PATENT OFFICE.

WILLIAM J. SLACK, OF LA GRANGE, INDIANA.

CISTERN.

SPECIFICATION forming part of Letters Patent No. 629,277, dated July 18, 1899.

Application filed February 1, 1899. Serial No. 704,197. (No model.)

To all whom it may concern:

Be it known that I, WILLIAM J. SLACK, of La Grange, in the county of La Grange and State of Indiana, have invented a new and useful Improvement in Cisterns, of which the following is such a full, clear, and exact description as will enable others skilled in the art to which it appertains to make the same, reference being had to the accompanying drawings, forming part of this specification, in which similar letters of reference indicate corresponding parts in all the figures.

Figure 1 is a vertical section of a cistern provided with my improvement. Fig. 2 is a plan view of the bottom and sediment-collector for such cistern. Fig. 3 is a side view of the same. Fig. 4 is a vertical section of a cistern provided with a modified form of bottom and sediment-collector.

It is the object of my invention to provide cisterns with an improved attachment for removal of foul water and sediment which collect therein.

It consists of an attachment which is cast or otherwise formed with circumferential flanges to adapt it for forming a water-tight joint with the wall of the cistern and with a central depression or cavity which is of conical form to adapt it to collect the sediment, and is also constructed with a discharge-passage which communicates therewith at a central point, as hereinafter more fully set forth.

Referring in the first instance to Figs. 1, 2, and 3, A indicates the side walls of the cistern, which may be formed of any suitable material, such as stone, brick, or cement. The bottom of the cistern converges, and the top a is provided with an inlet-pipe B. The conical bottom and sediment-collector C is formed or molded of any suitable material having due strength and durability. It is provided with parallel circumferential flanges, forming a groove c, which receives the adjacent edges of the walls A, as shown in Fig. 1, so that a water-tight joint is formed. The said bottom C slopes interiorly and is rounded at the apex, so as to form a smooth conical cavity or depression adapted for collection of sediment. Such cavity or depression is provided with a lateral discharge-passage c', which is curved and extends upward through the sloping side of the bottom C and connects with a discharge-pipe D, that extends nearly to the top of the cistern and thence diverges laterally. It is

apparent that if the cistern be filled the water, being above the lateral arm of pipe D, will be discharged by siphonic action and that this will occur automatically and continue so long as the water is maintained at due height. It is further apparent that by induction the sediment and foul water collected in the conical bottom C will be drawn off through the pipe D and discharged from the cistern.

E indicates a pump-stock through which pure water may be drawn off from the cistern.

I show in Fig. 4 a modified form C' of cistern-bottom and sediment-collector in which the discharge-passage c' is arranged exteriorly instead of interiorly, as in the preferred form of my invention before described. A discharge-pipe D' is connected with the exterior passage c' and extended upward outside of the cistern, as shown.

A screen F is arranged in the conical cavity of the cistern-bottom C and C', the same being supported upon and suitably secured to the sloping wall of the same. This screen is necessary to prevent passage of any object or substance which would tend to choke the passage c' or c'.

What I claim is—

1. A cistern attachment forming the bottom thereof and having a central, conical cavity, or depression, a curved discharge-passage communicating with the center thereof, and an eduction-pipe that communicates with such passage and extends upward to a point near the top of the cistern for use in drawing off sediment of foul water, as shown and described.

2. A cistern-bottom and sediment-collector constructed with a central, conical depression or cavity, a discharge-passage which communicates therewith and extends upward through its adjacent sloping surface, and a pipe connected with such passage and extending up through the body of the cistern, for use in drawing off sediment, substantially as shown and described.

3. The combination with the cistern-bottom and sediment-collector, having a central, conical depression, of a screen which rests and is secured upon the sloping wall of said bottom, substantially as shown and described.

WILLIAM J. SLACK.
